DESIGN FOR A JAR

Naurice M. Nesset, Glenview, Ill., assignor to
Baxter Laboratories, Inc., Glenview, Ill., a cor-
poration of Delaware

Application July 30, 1941, Serial No. 102,567

Term of patent 14 years

To all whom it may concern:

Be it known that I, Naurice M. Nesset, a citizen of the United States, residing at Glenview, county of Cook, and State of Illinois, have invented a new, original, and ornamental Design for a Jar, of which the following is a specification, reference being had to the accompanying drawing, forming a part thereof, in which:

Figure 1 is a side elevational view of a jar

showing my new design; and Fig. 2 a side elevational view, partly in longitudinal section.

The jar is substantially circular in transverse cross section throughout its length.

I claim:

The ornamental design for a jar, as shown and described.

NAURICE M. NESSET.
